**LIQUEFACTION AND SEPARATION OF AIR
COMPONENTS**

James K. La Fleur, Hermosa Beach, Calif., assignor to
The La Fleur Corporation, Torrance, Calif., a corpora-
tion of California

Filed Apr. 18, 1963, Ser. No. 273,883
8 Claims. (Cl. 62—22)

The present invention relates to the construction and arrangement of two rectifier columns usable for the liquefaction and substantially complete separation of the air components oxygen, argon, and nitrogen, and to processes for operating such columns and for achieving such liquefaction and separation, such columns to be operated at and such liquefaction and separation to take place at substantially atmospheric pressure.

Most of the advances in the prior art of air liquefaction and separation of the components oxygen, argon, and nitrogen have been those of pressure reduction. The prior art does not disclose the liquefaction and complete separation at substantially atmospheric pressure of the air components oxygen, argon, and nitrogen. Further, the art does not disclose such separation being accomplished in only two rectifier columns.

The problems of the prior art have not been due to an absence of adequate refrigeration but due to an improper use of that refrigeration available. The disclosure of the present invention presupposes means for achieving the desired and needed refrigeration. This refrigeration is preferably a gas having a critical temperature below that of nitrogen as it is desired to rectify in both columns at atmospheric pressure. Further, it is presumed that the needed amount of refrigeration is available. While the refrigeration must be adequate, the present invention makes a highly economical use of it so that the refrigeration used is at a minimum.

Thus, it is an object of the present invention to liquefy and separate the air components oxygen, argon, and nitrogen at substantially atmospheric pressure and by the use of only two rectifier columns.

Another object is that of constructing such rectifier columns so that in each column reflux may be accumulated and its rate of delivery to the plates may be controlled.

A further object of the invention is that of separating the components of air in only two columns so as to obtain oxygen, argon, and nitrogen with individual purities of better than 99.5 percent.

The above mentioned defects of the prior art are remedied and these objects achieved by a process and apparatus for the liquefaction and separation of air components in which a first and a second rectifier column is each supplied with top refrigeration for the formation of the reflux necessary for column operation, in which the refrigerant is a gas having a lower boiling point than nitrogen, in which the bottom of the first column collects the oxygen of the air and the bottom of the second column collects the argon of the air, in which the refrigerant passes first thru the second column and then thru the first column, and in which the air to be treated, before entering the first column at substantially atmospheric pressure, carries reboil heat to the first and then to the second column bottom.

The process and apparatus described briefly above is hereinafter set forth in detail and illustrated in the accompanying drawings, in which:

The figure is a schematic showing of two rectifier columns embodying the present invention and adapted to practice the process of the present invention.

In the present disclosure, there is no showing of apparatus or method for obtaining refrigeration of the refrig-

erant used in the columns. The cooling of the refrigerant such as neon, hydrogen, or helium to a temperature below that of the boiling point of nitrogen at substantially atmospheric pressure may be accomplished by any of the prior art methods. The refrigerant may be a single gas or a combination of gases. The amount of refrigeration, the heat removed from each column, is dependent on the quality and quantity of product to be removed therefrom. The operational drive for a column comes from the temperature differential between the bottom and the top thereof. This drive is regulated by the amount of heat supplied to the column bottom to evaporate liquid condensed therein and by the amount of refrigeration supplied to the top of the column. The heat supplied to the drive is a function of the amount of reflux, the downward moving condensate, which, in turn, is a function of the quality and quantity of the desired product.

Referring now to the flow of the gas to be separated, air being taken as the example, atmospheric air is drawn into a turbo-compressor 11 where it is compressed to approximately 45 p.s.i., after which it is treated in a treatment plant 12 to remove contaminants such as carbon dioxide, sulphur, and water, and then flows thru conduit 13 and one of two valves 14, 15 to one of two precoolers 16, 17. Here the air is cooled to about 177° R. (Rankine) by the counter-passage of uncondensed nitrogen leaving the top of the second 19 of two columns 18, 19, as will later be described. From the precoolers the air passes thru conduit 21 to one of two adsorbers 22, 23 that remove any remaining contaminants. The air is then directed by conduit 24 thru heat exchanger, or reboil, coils 26, 27 in series in the columns 18, 19, respectively, air emerging from the last coil at a temperature of about 163° R. In this connection, liquid oxygen accumulates at the bottom of the column 18 and liquid argon at the bottom of column 19, as will later appear. This 163° R. air is then led thru a conduit 28 to and expanded to substantially atmospheric pressure, 25 p.s.i.a., thru an expansion valve 29, and then introduced into the first, or oxygen, column 18 at substantially the composition point of air in the column, the point 31. The columns 18, 19, respectively, have means (not shown in detail), such as bubble cap trays 32, to bring the gas passing upward in the columns and thru the caps into intimate contact with condensed reflux liquid passing downward, over, and thru the trays therein. The columns 18, 19 are operated at close to atmospheric pressure. Refrigeration is provided by a cold coil 34, condenser coil, at the top of the oxygen column 18 to liquify some of the argon and nitrogen to provide the necessary reflux for the column operation. The flow of reflux from the condenser coil 34 to the trays is regulated by a reflux valve 35 below a storage vessel 36, or receiver. Liquid oxygen collects in the bottom of the column and is removed therefrom thru a conduit 37 secured to and thru the column bottom.

A saturated vapor mixture of nitrogen and argon flows as overhead product from the first column 18 thru a conduit 38 or as a liquid thru a valve 39 to the conduit 38 and then to the second column 19, the argon column, where the mixture is rectified into its argon and nitrogen components. The argon-nitrogen feed thru the inlet conduit 38 is to that portion of the column having the position point of the feed. The argon liquifies and collects in the bottom of the column for removal therefrom thru a drain conduit 41 secured to and thru such bottom. A large proportion of the nitrogen overhead is liquified by a cold coil 42 at the top of the column and the liquid nitrogen is removed by a conduit 43. Condensed nitrogen, also, provides the reflux liquid for the column, and its flow is controlled by a valve 44 from a condensate storage vessel 45, or receiver. Uncondensed nitrogen passes as part of the overhead thru a conduit 46 to the air

coolers 16, 17 from which it is exhausted as waste product at substantially ambient temperature.

In each of the rectifier columns 18, 19, heat is supplied at the bottom by the compressed air before it is expanded into the first column 18. As the air enters the first column 18, it passes upward thru the trays 32 and into intimate contact with the oxygen-argon-nitrogen liquid thereon, which is descending from tray to tray, to give up its oxygen content thereto. A stream of vapor rises in the column and at each upward stage the vapor becomes poorer in oxygen and richer in nitrogen and argon, while the descending argon-nitrogen liquid, the reflux, becomes richer in oxygen and leaner in argon and nitrogen. It will be apparent that it does not require many stages of successive liquefaction and evaporation to produce a vapor mixture of pure nitrogen and argon at the column top and pure liquid oxygen at the column bottom, provided that the temperature conditions are such as to tend to bring the ascending vapor into equilibrium with the liquid at the various stages, or plates, found necessary by design and test calculations. The refrigerative effect producing liquefaction of the argon-nitrogen mixture in the top of the column and of the liquid oxygen which collects in the bottom of the column comes from the cold coil 34, or condenser, in the top of the column, which coil acts as a heat sump for the column. The heat exchange coil 26 in the bottom of the column transfers heat from the incoming air to the liquid bottom oxygen to vaporize a portion thereof to provide an upward vapor flow to remove argon and nitrogen from the downwardly moving liquid. This vaporized oxygen is condensed on the plates thereabove by the descending liquids from thereabove. The temperature differential maintained between the bottom and the top of the column constitutes the drive of the column to effect the rectification and condensation taking place therein. The absolute temperatures maintained in the column determine the type of products obtained, and the heat transfer rate determines the amount of overhead product obtained within design limits.

The operation of the second column 19 is in principle the same as that of the oxygen column, resulting in the separation of nitrogen and argon, and the production of these gases in liquid form with some gaseous nitrogen passing out thru the overhead conduit 46 leading to the air precoolers 16, 17. The argon-nitrogen vapor is led from the first column 18 into the second column 19 at substantially its composition point, that point in the column having vapor of the same composition. Pure liquid nitrogen condensed in the top of the column 19 by the cold coil 42 supplies the reflux liquid which descends thru the column to become enriched with argon and to lose nitrogen in the process until at the bottom of the column the liquid is pure argon.

Any of the rare gases which may be present in the air are found with the liquid oxygen or in the vented nitrogen gas, but this does not detract from the fact that there is a complete separation of oxygen, argon, and nitrogen by the use of only two rectification columns. Product purity is between 99.5% and 99.995% for these gases.

It is to be noted that the flow of refrigerant is first to the second column 19, the argon column, and then to the first column 18, the oxygen column, and that the flow of the input air for heating the column bottoms is first to the bottom of the first column 18 and then to the bottom of the second column 19. Thus, in the columns the flow of refrigerant is counter current to the flow of incoming air as it is being precooled by such refrigerant. And, thus, the oxygen column is acted on by the warmer air and refrigerant, and the argon column by the colder air and refrigerant, which is as it should be as the oxygen has the highest boiling temperature of the three gases being condensed and separated.

Having thus described my invention, its construction and operation, I claim:

1. A process for the rectification of air to yield oxygen, argon, and nitrogen, that comprises: establishing a first and a second rectification zone, passing a stream of air in heat exchange relationship with said first and then said second zone to provide reboil heat for said zones, then passing said stream of air to said first zone for rectification therein into liquid oxygen product and an overhead of argon and nitrogen, passing a separate and independent stream of refrigerated gas selected from the group consisting of helium, hydrogen and neon in heat exchange relationship with said second zone and then with said first zone to provide reflux for said zones, removing said liquid oxygen and said overhead of argon and nitrogen from said first zone, introducing said argon and nitrogen overhead to said second zone for rectification therein to liquid argon product and an overhead of nitrogen, and removing said liquid argon and said nitrogen overhead from said second zone.
2. A process as defined in claim 1 in which said refrigerated gas is refrigerated below the temperature of liquid nitrogen at the pressure in said second zone.
3. A process for separating oxygen, argon and nitrogen from air, that comprises: treating the air in a primary rectification zone in such a manner as to produce therein a liquid oxygen product fraction and an argon-nitrogen overhead, transferring said argon-nitrogen overhead to a secondary rectification zone wherein it is treated to produce therein liquid argon product fraction and a nitrogen overhead, and removing said liquid argon and nitrogen overhead from said secondary zone; and prior to treating said air in said primary zone, passing it in heat exchange relationship with said primary zone and then said secondary zone to provide reboil heat for said zones, and passing a separate and independent stream of refrigerated gas selected from the group consisting of helium, hydrogen and neon, in heat exchange relationship with said secondary zone and then said primary zone to provide reflux for said zones.
4. The combination of claim 3 in which said refrigerated gas is refrigerated below the temperature of liquid nitrogen at the pressure in said secondary zone.
5. The method of separating out substantially pure components of oxygen, argon and nitrogen from air which comprises introducing air into a first rectification zone at substantially the composition point of air in said zone and at a pressure close to but somewhat above atmospheric pressure, rectifying in said zone to remove liquid oxygen from the bottom thereof substantially free of argon and nitrogen and removing argon and nitrogen as overhead from said first zone, passing said argon and nitrogen directly to a second rectification zone at substantially their composition point in said second zone and at a pressure somewhat above atmospheric but less than the pressure in said first zone, rectifying the mixture of argon and nitrogen to remove liquid argon free of nitrogen from the bottom of said second zone and nitrogen as overhead from said second zone, said nitrogen being removed as overhead from said second rectification zone at a pressure sufficiently above atmospheric to cause said nitrogen to flow as overhead from said second rectification zone, and said air being introduced to said first rectification zone at a pressure sufficiently above atmospheric to cause the flow through said first and second rectification zones, refrigerating the top of each of said zones by heat exchange therewith of a separate and independent gas refrigerant selected from the group consisting of helium, hydrogen and neon, by passing said gas to said second zone and then to said first zone in series, said gas as it is passed to said second zone being at a temperature below the temperature of liquid nitrogen at the pressure in said second zone, and prior to introduction of said air into the first rectification zone, passing said air in heat exchange relation with the bottom of said first rectification zone.

zone and then with the bottom of said second rectification zone to provide reboil heat for said zones.

6. The method of claim 5 in which the liquid oxygen, the liquid argon, and the nitrogen overhead from said second zone are of a purity of 99.5% to 99.995%.

7. The method for separating out the components of oxygen, argon, and nitrogen from air which comprises introducing air into a first rectification zone at approximately atmospheric pressure, rectifying in said zone to remove oxygen as a product from the lower portion of said zone and a mixture of argon and nitrogen as overhead from said zone, passing said argon and nitrogen to a second rectification zone, rectifying the mixture of argon and nitrogen to remove argon as a product from the lower portion of said second rectification zone and removing nitrogen as an overhead product of said second zone, and refrigerating the top of each of said zones by heat exchange therewith of a separate and independent gas refrigerant selected from the group consisting of helium, hydrogen and neon, by passing said gas to said second zone and then to said first zone, said gas as it is passed

10

to said second zone being at a temperature below the temperature of liquid nitrogen at the pressure in said second zone, and prior to introduction of said air into the first rectification zone, passing said air in heat exchange relation with the bottom of said first rectification zone and then with the bottom of said second rectification zone to provide reboil heat for said zones.

8. The method of claim 7 in which the removed oxygen, argon, and nitrogen are of a purity of 99.5% to 99.995%.
